COUPLED CIRCUITS

Paul O. Farnham, Boonton, N. J., assignor to
Radio Frequency Laboratories, Incorporated,
Boonton, N. J., a corporation of New Jersey

Application March 21, 1932. Serial No. 600,358

10 Claims. (Cl. 178—44)

This invention relates to coupled circuits and particularly to methods of and circuit arrangements for varying the coupling coefficient between two circuits without varying the natural resonant frequencies of the circuits and/or of the transmission line in which said circuits are incorporated.

Transmission systems which include two circuits tuned to the same frequency and coupled with somewhat more than critical coupling act as "band pass" filters as the resonance curve of the coupled circuits is not a single sharp peak but comprises a relatively flat-topped curve resulting from the combination of two spaced resonance curves. The mean or "natural" frequency of the coupled circuits is the resonant frequency of the separate circuits and the two peaks of the resonance curve are spaced from the natural resonant frequency by an amount that varies with the coefficient of coupling of the two circuits. With less than critical shape coupling, the resonance curve has only one peak but the condition still obtains that the width and shape of the curve depend upon the coefficient of coupling; see Proceedings Institute of Radio Engineers, June, 1930, page 983.

It would be desirable, both in the operation of a transmission system and in its adjustment, to change the width of the resonance curve without changing the natural frequency of the coupled circuits. The coupling systems previously employed have not permitted this operation as a change in the coupling efficiency has resulted in a change in the resonant frequency of the individual circuits, thereby changing the natural frequency of the coupled circuits.

An object of the present invention is to provide coupled circuits capable of adjustment to vary the width of the resonance curve without affecting the natural resonant frequency. A further object is to provide tuned circuits that are coupled by a tuned impedance that may be effectively removed from the network to change the coupling efficiency. More specifically, an object is to provide a system of two circuits tunable to the same frequency and which include coupling impedances that are also tuned to the same frequency, and switches for short-circuiting the coupling impedances, thereby to alter the coupling coefficient of the two circuits without affecting the natural resonant frequency of the system.

These and other objects and advantages of the invention will be apparent from the following specification when taken with the accompanying drawing wherein:

Fig. 1 is a circuit diagram of an embodiment of the invention, and

Fig. 2 is a curve sheet illustrating the resonance curves obtainable with a coupling system such as shown in Fig. 1.

In the drawing, the reference numerals 1, 1 and 2, 2 identify, respectively, the input and the output terminals of a network that forms two coupled circuits. The input circuit I includes ohmic resistance R_1 , a main inductance L_1 , a coupling inductance L_a , the coupling capacity C_m , and a tuning condenser C_1 . Similarly, the output circuit II includes resistive impedance R_2 , inductances L_2 and L_b , the coupling capacity C_m and a tuning condenser C_2 . A capacitive coupling C and inductive coupling M between the two circuits are indicated, but either or both of these couplings may be substantially zero.

Switches 3 are provided for short-circuiting the coupling impedances of the circuits and, as indicated by the broken line 4, these switches are preferably mechanically connected for simultaneous operation.

When the switches are closed, the coupling between circuits I and II is preferably very weak, approaching zero when C and M are zero, and the resonance curve has a single peak, as shown by curve A of Fig. 2. For simplicity of explanation, it will be assumed that both circuits are tuned to the same frequency. Under these conditions, the resonant frequency f is given by the equations:

$$\omega = \frac{1}{\sqrt{L_1 C_1}} = \frac{1}{\sqrt{L_2 C_2}} \quad (1)$$

$$\omega = 2\pi f \quad (2)$$

In accordance with the invention, the values of the reactances of the short-circuited coupling system are so related as to satisfy the equation:

$$\frac{1}{\sqrt{L_a C_m}} = \frac{1}{\sqrt{L_b C_m}} = \omega \quad (3)$$

Under these conditions, opening of the switches 3 to include the coupling impedances in the circuits I and II will not alter the resonant frequency f of the system as this operation introduces series impedances in each circuit that are purely resistive at that frequency.

The transmission efficiency of the coupling system, i. e. the ratio of the output voltage E_1 to the input voltage E varies with frequency as shown by the resonance curve B of Fig. 2. Curve B has two peaks and therefore indicates that the total coupling between circuits I and II is greater than critical shape coupling, but it will be ap-

parent that the same absence of any change in the natural frequency f will attend the application of the invention to circuits in which the coupling is less than critical shape.

5 As indicated in Fig. 1, a magnetic coupling $-M_1$ may be provided between the inductances L_a , L_b of the coupling impedance. With magnetic coupling present, the total coupling controlled by switches 3 will be:

$$10 \quad X_m = \pm \omega M^1 - \frac{1}{\omega C_m} \quad (4)$$

To secure economy and tolerance, the sign of the magnetic coupling should be negative in order that the mutual inductive coupling will aid the capacitive coupling C_m . Inductive coupling is not necessary, however, so long as Equation (3) is satisfied.

With the coupling impedances L_a , L_b , C_m and, 20 if employed, $-M_1$, so related that the natural resonant frequency is not altered by the position of switches 3, it will be apparent that the relatively permanent couplings C and/or M may be adjusted for less than critical shape coupling, 25 i. e. to give a comparatively sharp peak for the resonance curve. This adjustment is, of course, effected with the switches 3 closed to short-circuit the complex coupling impedance. The opening of switches 3 introduces a further coupling to 30 broaden the resonance curve without changing the natural resonant frequency. The magnitudes of the coupling impedance may be chosen to give any desired broadening of the resonance curve.

The invention is applicable not only to coupling systems in which the separate circuits are 35 tuned to the same frequency f , but also to systems in which the individual circuits are tuned to different frequencies. In addition to its obvious use for varying the characteristics of a circuit 40 during the transmission of signals, the invention may be used to facilitate the adjustment of the several elements of a circuit. The alignment of the intermediate frequency circuits of a super-heterodyne receiver is quite difficult when more 45 than critical shape coupling is employed in band-pass circuits. Circuits designed as above described are readily adjusted by first short-circuiting the coupling impedances and then tuning each of the circuits I and II to the intermediate frequency f on which the oscillator tracking is based. The low coupling efficiency makes 50 this adjustment practical as the tuning of one circuit does not affect the resonant frequency of the other circuit.

55 When the main circuits are to be tuned over a band of frequencies, the coupling condenser C_m may be mechanically connected to the tuning condensers to maintain the relationships expressed by the above equations throughout the 60 tuning range of the circuits.

I claim:

1. The combination with two circuits, and a reactive coupling between said circuits, of reactive means for varying the coefficient of coupling between said circuits while maintaining their natural resonant frequency unchanged; 65 said reactive means comprising serially connected

reactances coupling said circuits and resonating at the said natural frequency, and means for alternatively including said reactances in and excluding the same from said circuits.

2. A pair of circuits each including main and auxiliary reactances, in each circuit the main and auxiliary reactances being resonant at the same frequency, a coupling between the auxiliary reactances of said circuits, and means for changing the coefficient of coupling between said circuits without altering the natural resonance frequency of said coupled circuits.

3. The invention as set forth in claim 2, where- 90 in said means comprises switch means for including said auxiliary reactances in or excluding the same from their respective circuits.

4. A pair of resonant circuits each including reactances coupled to provide less than critical shape coupling, and means adapted to increase the coupling to more than critical shape coupling, 95 said means comprising coupling reactances and switch means for connecting said coupling reactances into the respective circuits, said coupling reactances including a common portion and portions for introduction into the respective circuits, 100 and each of said last portions resonating with said common portion at the resonant frequency of the circuit into which the respective last portions may be introduced.

5. In a transmission circuit, the combination 105 with a tuned circuit and a second tuned circuit coupled thereto, of a coupling impedance including a reactance of one type and a pair of reactances of the opposite type, and switch means for connecting said coupling impedance into said 110 two circuits.

6. In a transmission circuit, the combination 115 with a tuned circuit and a second tuned circuit coupled thereto, of a coupling impedance including a reactance of one type and a pair of reactances of the opposite type, and switch means for connecting said first reactance into both of 120 said circuits and for connecting the reactances of said pair into the respective circuits.

7. The combination with a pair of circuits 120 tuned to the same frequency and coupled to resonate as a whole at that frequency, of means for varying the coefficient of coupling between said circuits, said means comprising an impedance having two branches each resonating at the said 125 frequency.

8. A pair of tuned circuits each including inductance and a capacity, a second capacity common to and coupling said circuits, of means for short-circuiting said common capacity and such 130 portions of the inductance of each of said circuits that the short-circuited reactances resonate at the natural resonance frequency of the coupled circuits.

9. The invention as set forth in claim 8, where- 135 in the said portions of said inductances are coupled magnetically.

10. The invention as set forth in claim 8, where- 140 in the said portions of said inductances are coupled magnetically to add to the capacitive coupling of said common capacity.

PAUL O. FARNHAM.
